UNITED STATES PATENT OFFICE

JOSEPH W. LEGG, DECEASED, LATE OF WILKINSBURG, PENNSYLVANIA, BY ESTHER L. LEGG, ADMINISTRATRIX, OF WORCESTER, MASSACHUSETTS, ASSIGNOR TO WESTINGHOUSE ELECTRIC & MANUFACTURING COMPANY, A CORPORATION OF PENNSYLVANIA

LIGHT SOURCE CONTROL SYSTEM

Original application filed June 7, 1926, Serial No. 114,187. Divided and this application filed June 3, 1929. Serial No. 367,977.

This invention relates to oscillographs and particularly to means for controlling the light sources thereof.

One object of the invention is to provide means for controlling the light source of an oscillograph or similar device that shall permit of instantaneous illumination of the instrument.

Another object of the invention is to provide means for maintaining the filaments of light sources for oscillographs at a desired temperature after being heated instantaneously.

A further object of the invention is to provide means for suddenly applying an abnormal voltage to an electro-responsive device and for immediately thereafter maintaining a reduced voltage across said device.

A still further object of the invention is to provide control means for an oscillograph that shall condition the same for instant response during long periods of time to record conditions on a commercial transmission line when a short circuit or like phenomenon occurs.

In the prior art, the light sources of electric indicating devices, such as oscillographs, are not supplied with any means for accelerating the heating thereof, and, therefore, an appreciable length of time is required before enough energy is supplied to the light source to cause it to emit light of sufficient intensity to permit the instrument to function.

The time consumed in bringing a light source, such as the filament of an incandescent lamp, to the required degree of incandescence is so great that it is necessary to await the energization of the light source and make photographs by employing a shutter. This complicates the apparatus and also renders the instrument useless for recording such momentary phenomena as are caused by a chance short circuit on a commercial power line. The filament does not reach incandescence rapidly enough to permit a record of the first part of a momentary phenomenon or transient to be obtained.

In practicing the invention, the filament of an incandescent lamp is heated to a high

temperature in a very brief period of time by the discharge through it of a quantity of electrical energy stored in an inductance coil, and the filament is subsequently maintained at a desired temperature by means of another energy supply. The time consumed to provide the illumination necessary for the operation of the instrument is so brief as to be almost negligible, and no shutter need be utilized. Furthermore, the filament comes to incandescence so rapidly that the first part of a transient may be recorded.

This application is a division of copending application, Serial No. 114,187, filed June 7, 1926.

Other features and advantages of the invention will appear from the following description, taken in connection with the accompanying drawing the single figure of which illustrates diagrammatically, an embodiment of the invention in which a transformer supplies the stored electrical energy.

Referring to the drawing, the apparatus comprises, in general, an incandescent lamp 1, a transformer 2, a storage battery 3, a rectifier 4 shunted by resistance 5 and a control relay 6. The incandescent lamp 1 and the control relay 6 are of usual types. The control relay 6 is a quick-acting relay which is normally closed and so connected to a transmission line 7 that it will be opened when a short circuit occurs on the line.

The transformer 2, which may be of the conventional type, is so designed as to step down the alternating current supplied to the input thereof to a proper value for lighting the incandescent lamp 1, during the period that photographs are being made by the oscillograph. The transformer comprises an iron core 8, a primary coil 9 and a secondary coil 10, the primary coil having many more turns than the secondary coil.

The rectifier 4 is a one-way rectifier of conventional design adapted to rectify alternating current flowing therethrough and to supply the rectified current to the storage battery 3.

When the control relay 6 is closed, three circuits are provided by the above-described elements; a pulsating-current circuit 11, a

100

continuous-current circuit 12 and a circuit 13 which carries current only when the instrument is in operation.

The pulsating-current circuit 11 extends from terminals 14 which are connected to a source of alternating current (not shown) through the upper portion of the resistor 5, through the rectifier 4, the contact members of the control relay 6, the battery 3 and back to the other terminal 14. A relatively large quantity of current flows in the pulsating-current circuit 11 to cause a large drop of potential in the upper portion of the resistor 5, the rectifier 4 being connected across a sufficiently long portion of the resistor 5 to provide an easier path for the pulsating current, with the result that virtually all of the current flows through the rectifier 4 and is rectified to pass through the battery 3 and maintain it in charged condition.

The continuous-current circuit 12 extends from one terminal of the battery 3 through the primary coil 9 of the transformer and across the contact members of the control relay 6 to the other terminal of the battery 3. The continuous current maintains a strong electro-magnetic field in the core of the transformer 2.

30 The circuit 13 comprises the secondary winding 10 of the transformer and the light source 1.

The control relay 6 is so connected to the transmission line 7, by means of a transformer 15, that, when current of abnormal value appears on the line, the contact points of the relay 6 will be opened.

The disturbances which occur on the transmission line 7 are recorded on a photographic film 16 in accordance with the deflections of an oscillograph deflecting element 17 which may be connected, in the usual manner, across the line 7 through a resistance element 18.

45 When the control relay 6 is actuated in response to a disturbance on the transmission line, the relay contacts are opened, and the circuit 12, which carries the current maintaining the electro-magnetic field in the core of the transformer 2, is broken, and the stored electric energy in the core discharges instantaneously through the secondary coil 10, thereby providing sufficient current to heat the filament of the lamp 1 to a high degree of brilliancy in a very short time.

The opening of the contact members of the control relay 6 also breaks the pulsating-current circuit, and the alternating current which is supplied to the terminals 14 takes a new course which includes the entire length of the resistor 5, the primary coil 9 of the transformer and the conductor 19.

60 Oscillographs without a shutter or with the shutter open and supplied with a con-

tinuously rotating photographic film may be so electrically connected to a commercial transmission line as to automatically record the current pulsations when any short circuit sufficient to operate the control relay 70 occurs. By this means, records may be obtained of the actual phenomena of a commercial circuit without entailing the risk and expense incidental to an experimental short circuit which is required at the present 75 time because the oscillograph of the prior art requires an appreciable time for the light source to heat up to full brilliancy.

Various modifications may be made in the invention without departing from the spirit and scope thereof, and it is desired, therefore, that only such limitations shall be placed thereon as are shown by the prior art and set forth in the appended claims.

80 What is claimed:

1. Electrical apparatus comprising an electro-responsive device, a transformer having a primary and a secondary, said electro-responsive device being connected to said secondary, a storage battery, means for charging said battery through a charging circuit, means for passing a continuous flow of direct current from said battery through said primary while said battery is being charged, and means for suddenly interrupting the flow of direct current through said primary and for simultaneously breaking said charging circuit.

2. In combination, an electro-responsive device, a transformer having a primary and a secondary, said electro-responsive device being connected to said secondary, a storage battery, means including a charging circuit for normally passing a charging current through said battery, means including a portion of said charging circuit for connecting said battery to said primary whereby a continuous flow of direct current is normally maintained therethrough, and means for interrupting said portion of the charging circuit whereby the flow of direct current through said primary is interrupted.

3. Electrical apparatus comprising an electro-responsive device, a transformer having a primary and a secondary, said electro-responsive device being connected to said secondary, a storage battery, means including a rectifier for charging said battery, an impedance unit connected in shunt to said rectifier, means for passing a flow of direct current from said battery through said primary, means for interrupting said flow, and means including said impedance unit for maintaining a flow of alternating current through said primary immediately after the interruption of said flow of direct current.

4. Electrical apparatus comprising a transformer having a primary and a secondary, an electro-responsive device connected

to said secondary, means for passing a flow of direct current through said primary, means for interrupting said flow of direct current, and means for passing a continuous flow of alternating current through said primary in response to the interruption of said flow of direct current.

5. Electrical apparatus comprising a transformer having a primary and a secondary, an incandescent lamp connected to said secondary, means for passing a flow of direct current through said primary, means for interrupting said flow of direct current in response to an electrical disturbance, and means for passing a continuous flow of alternating current through said primary in response to said interruption.

6. Electrical apparatus comprising a transformer having a primary and a secondary, a light source connected to said secondary, means for passing a flow of direct current through said primary, and means for inducing a continuous flow of alternating current in said secondary in response to the interruption of said flow of direct current.

In testimony whereof, I have hereunto subscribed my name this 27th day of May, 1929.
